(57) **CLAIM**

The design for an optical filter clamp, as shown and described.

DESCRIPTION

FIG. 1 is a top left perspective view of the optical filter clamp showing our new design in an open position.

FIG. 2 is a left side view thereof.

FIG. 3 is a right side view thereof.

FIG. 4 is a top view thereof.

FIG. 5 is a bottom view thereof.

FIG. 6 is a front view thereof.

FIG. 7 is a rear view thereof.

FIG. 8 is a top left perspective view of the optical filter clamp shown in a first alternate position in an environment of use; and,

FIG. 9 is a bottom left perspective view of the optical filter clamp shown in a second alternate position in an environment of use.

The broken lines depict portions of the article and environmental structure that form no part of the claimed design.
